UNITED STATES PATENT OFFICE.

CHARLES E. JONES, OF LYNCHBURG, VIRGINIA, ASSIGNOR TO THE GLA-MORGAN PIPE AND FOUNDRY COMPANY, OF LYNCHBURG, VIRGINIA.

FIRE-HYDRANT.

SPECIFICATION forming part of Letters Patent No. 723,532, dated March 24, 1903.

Application filed January 21, 1902. Serial No. 90,680. (No model.)

To all whom it may concern:

Be it known that I, CHARLES E. JONES, a citizen of the United States, residing at Lynchburg, in the county of Campbell and State of Virginia, have invented a new and useful Fire-Hydrant, of which the following is a specification.

This invention relates to fire-hydrants wherein the controlling-valve thereof is normally seated by the water-pressure from the main, and has for its object to provide an improved hydrant of this type wherein the controlling-valve is readily manipulated, so as to be opened against the water-pressure. Heretofore in this type of hydrant the valve has usually been held upon the valve-stem by a pair of nuts which clamp against the valve, whereby the screw-threaded joint between the valve and the stem forms a passage through which the water under pressure is forced into the body of the hydrant and a serious leakage results.

In view of these disadvantages it is the essential object of the present invention to provide a water-tight joint or connection between the valve and the valve-stem, so as to effectively prevent the water from the main leaking into the body of the hydrant when the valve is closed.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a side elevation of a hydrant embodying the present invention. Fig. 2 is a longitudinal sectional view thereof. Fig. 3 is an enlarged detail sectional view taken through the improved valve to illustrate the water-tight joint between said valve and the valve-stem.

Like characters of reference designate corresponding parts in all the figures of the drawings.

Referring to the accompanying drawings,

it will be seen that the body of the present hydrant comprises a lower upstanding cylindrical shell member 1 and an upper shell member 2, fitted into the lower or outer shell member through the open top thereof. The outer member is provided with a bottom marginal flange 3, to which is bolted an elbow-base 4, having its horizontal branch provided with a coupling portion 5 for engagement with a water-main. The inner or upper shell-section is provided with a pendent cylindrical flange 6, which embraces the upper flanged end of the outer shell member 1 and is bolted thereto by a plurality of bolts 7, so as to hold the lower end of the inner shell snugly against the upper packing-ring of a removable valve-seat 8, supported upon an annular flange 9 of the elbow-base 4. The upper end portion of the shell 2 is provided with a plurality of hose-couplings 10 of different diameter, so that several different gages of hose may be connected to the hydrant.

Located centrally within the body of the hydrant is a polygonal valve-stem 11, the upper end of which works in a guide-casing 12, pendent from the top of the shell member 2 and provided at its lower end with a polygonal opening for the reception of the valve-stem, thereby to prevent turning of the latter. Projected through the top of the casing 2 is a rotatable key-post 13, the lower end portion of which is tubular and interiorly screw-threaded for the reception of a correspondingly screw-threaded reduced upper-terminal 14 of the valve-stem. The upper end of the valve-post is projected exteriorly of the hydrant and made polygonal, as at 15, for the reception of a suitable key, whereby the post may be turned and the valve-stem thereby moved in an endwise direction, so as to unseat the valve at the lower end of the stem. As best illustrated in Fig. 3, it will be seen that the lower end of the valve-stem is reduced, and the opposite end portions of this reduced part are screw-threaded, as indicated at 16 and 17, respectively, the intermediate portion, which lies between the two screw-threaded portions, being smooth. A nut 18 is fitted to the inner or upper screw-threaded portion 16, and against the under side of this nut lies a metallic head or washer 19. A simi-

lar head or washer 20 is fitted to the terminal screw-threaded portion, and between the two heads is a compressible washer 21, of rubber, leather, or other suitable material. It will 5 here be noted that the lower head or washer is not provided with an opening extending entirely through the same, as is true of other hydrant-valves, but is provided in its upper portion with a screw-threaded socket 22, the 10 lower end of which is closed, whereby the joint between the valve and the lower end of the stem is entirely closed, so that it is impossible for water to be forced upwardly through the valve and into the body of the 15 hydrant. For convenience in fitting the lower head or section to the valve-stem the outer or lower face of the section is provided with a central polygonal wrench-head 23. A central pendent tubular guide-socket 24 is formed 20 integrally with the lower valve head or section 20, the lower end of this socket being open, so as to telescope upon the guide-pin or projection 25, carried by the bottom of the elbow-base 4. By this arrangement the valve 25 is effectively guided in its movement by a guide which is located externally of the body of the hydrant, so that the latter may be entirely unobstructed throughout its entire interior area. As clearly shown in Fig. 3, it 30 will be seen that the wrench-seat 23 is located externally upon the guide member 24, which telescopes upon the pin 25, and instead of being at the base of the guide it may be located at any point thereon. It will of course be 35 understood that the marginal edge of the valve-body 21 is beveled or shaped so as to properly engage the lower side of the valve-seat 8, and said valve reciprocates vertically within the base 4.

40 The upper portion of the base 4 is provided with a vent-perforation 26, which is in communication with an upright tubular valve-casing 27, which is carried by the valve-seat 8. The upper end of this casing is open for 45 the reception of a spring-actuated valve-plunger 28, having a laterally-offset and pendent trip 29, the lower end of which lies in the path of the upward movement of the controlling-valve, so that when the controlling-valve 50 is closed the vent will be opened, thereby to drain all of the water from the interior of the hydrant. The inner shell 2 is provided with an inner lateral projection 30, and a spring 31 is interposed between this lug and the valve 55 28, so as to seat the same when the controlling-valve is depressed out of engagement with the trip 29.

That portion of the body of the hydrant which is under ground is surrounded by a sectional jacket 32 to form a dead-air space 60 about the hydrant for the purpose of protecting the latter against frost.

From the foregoing description it is apparent that the present controlling-valve is normally seated by the pressure of the water 65 from the main and is released by manipulating the key-post 15, so as to force the valve downwardly and thereby permit of the water rising into the body of the hydrant and thence outwardly through one or more of the discharges formed by the hose-couplings 10. Furthermore, by having the lower metallic 70 valve-section in the nature of a cap or, in other words, provided with a screw-threaded socket having its inner end closed and receiving a screw-threaded portion of the valve-stem the under surface of the valve is entirely 75 free from joints, whereby there are no passages in the valve through which the water may escape into the interior of the hydrant. 80

What I claim is—

1. A pressure-valve, comprising a valve-stem having a screw-threaded terminal, a compressible valve-body applied to the screw-threaded end of the stem, and a pair of valve-clamping members also applied to the screw-threaded end of the stem and snugly embracing the body, the inner face of the outer member being provided with a screw-threaded socket receiving the screw-threaded terminal 85 of the stem, and the inner end of said socket being closed by an integral wall, the outer face of said member being entirely free from joints and also provided with a longitudinally-projected and open-ended tubular guide- 90 socket.

2. In a hydrant, the combination with a shell, and a valve-seat therein, of a valve-stem having a screw-threaded terminal, and a pressure-valve having a screw-threaded 100 socket receiving the screw-threaded end of the stem, the opposite face of the valve being free from joints and provided with a guide-socket, and a guide projection carried by one of the walls of the hydrant and projected into 105 the guide-socket.

In testimony that I claim the foregoing as my own I have hereto affixed my signature in the presence of two witnesses.

CHARLES E. JONES.
